CLAIM

The ornamental design for a farmhouse chandelier, as shown and described.

DESCRIPTION

FIG. 1 is a perspective view of a farmhouse chandelier design showing my new design.

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the upper right corner of the farmhouse chandelier taken from the short-dash-long-dash encircled portion in FIG. 1.

The broken lines in the drawings illustrate the portions of the farmhouse chandelier which form no part of the claimed design. The additional short-dash-long-dash broken lines encircling the enlargement areas in FIGS. 1 and 9 depict the boundaries of the enlargement and form no part of the claimed design.
